UNITED STATES PATENT OFFICE.

DAVID M. PARRY AND THOMAS H. PARRY, OF INDIANAPOLIS, INDIANA.

VEHICLE-SHAFT.

SPECIFICATION forming part of Letters Patent No. 415,732, dated November 26, 1889.

Application filed August 8, 1889. Serial No. 320,156. (No model.)

To all whom it may concern:

Be it known that we, DAVID M. PARRY and THOMAS H. PARRY, citizens of the United States, residing at Indianapolis, in the county 5 of Marion and State of Indiana, have invented certain new and useful Improvements in Vehicle-Shafts; and we do hereby declare the following to be a full, clear, and exact description of the invention, such as will enable 10 others skilled in the art to which it appertains to make and use the same.

This invention relates to improvements in vehicle-shafts and in the art of making the same, the object of the invention being to 15 produce a shaft which shall be cheap, durable, and ornamental, and which shall be provided with a tip that is not liable to become loose and knocked off, and which will obviate the rattling so common to shaft-tips of ordinary 20 construction.

The invention consists in certain details of construction and arrangement of parts of the said shaft and in certain improvements in the art of making said shaft, substantially as 25 hereinafter described, and set forth in the claim.

Figure 1 represents in side elevation a portion of a shaft embodying our improvements; Fig. 2, a longitudinal section of the same; 30 Fig. 3, a cross-section on dotted line $x-x$, Fig. 2; and Fig. 4, a sectional detail showing a modification.

In the drawings, A represents the vehicle-shaft, a portion only of which is shown. 35 Formed at a short distance from both forward ends of the shaft is a shallow groove B, which extends entirely around the same. Into this groove B will preferably be fixed a me-

tallic strip C, which strip takes the place of the usual cone-shaped tip, and will be secured 40 in the groove B, as shown in the drawings, in such manner that it cannot be readily displaced, its edges coming flush with the periphery of the shaft.

In practice we have found this construction highly advantageous, as it forms a very ornamental tip, which is cheap and will not rattle or become displaced.

Instead of securing a metallic strip in the groove B, said groove may be painted in gold 50 or silver, if desired.

The manufacture of the shaft is as follows: The shaft after its main body is finished will have its ends tapered and rounded off. The groove B will then be cut therein, after which 55 the whole shaft is painted the desired color, and the groove B will then be ornamented by a strip of metal or painted in imitation of metal.

We claim—

The shaft A, having its ends rounded and having the groove B, semicircular in cross-section, formed entirely around the shaft near each end, in combination with the metal strip C, which is also semicircular in cross-section, 65 fixed in said groove with its side edges flush with or below the periphery of the shaft, substantially as described.

In testimony whereof we affix our signatures in presence of two witnesses.

DAVID M. PARRY,
THOMAS H. PARRY,
